UNITED STATES PATENT OFFICE

102,186

DESIGN FOR A FLOOR SURFACING MACHINE

William E. Holt, Newark, N. J.

Application March 28, 1936, Serial No. 61,832

Term of patent 14 years

To all whom it may concern:

Be it known that I, William E. Holt, a citizen of the United States, residing at Livingston, in the county of Essex and State of New Jersey, have invented a new, original, and ornamental Design for Floor Surfacing Machines, of which the following is a specification, reference being had to the accompanying drawing, forming part thereof.

Fig. 1 is a perspective view of a floor surfacing machine, showing my new design; and

Fig. 2 is a perspective view looking at the opposite side of the machine, a portion of the dust bag being broken away for convenience of illustration.

I claim:

The ornamental design for a floor surfacing machine, as shown and described.

WILLIAM E. HOLT.
